UNITED STATES PATENT OFFICE.

ALVA A. PATTON, OF SAN FRANCISCO, CALIFORNIA, ASSIGNOR OF ONE-HALF
TO GEORGE H. LARKIN, OF SAME PLACE.

BOILER-TUBE CLEANER AND DRIVER.

SPECIFICATION forming part of Letters Patent No. 634,270, dated October 3, 1899.

Application filed January 26, 1899. Serial No. 703,493. (No model.)

To all whom it may concern:

Be it known that I, ALVA A. PATTON, a citizen of the United States, residing in the city and county of San Francisco, State of California, have invented an Improvement in Boiler-Tube Cleaners and Drivers; and I hereby declare the following to be a full, clear, and exact description of the same.

My invention relates to a device for cleaning the interior of steam-boiler tubes either of that class which are known as "water-tube boilers," in which the water is contained within the tubes and the heat applied to the exterior, or those surrounded by water and through which the fire passes. Such tubes become coated in a short time with deposits and it is necessary to clean them, and my device is designed to rapidly and effectively perform this duty.

It consists in the parts and the constructions and combinations of parts hereinafter described and claimed.

Referring to the accompanying drawings, Figure 1 is a longitudinal sectional view of my device. Fig. 2 is a transverse section taken through the lower part of the driver, the upper part removed to show the cleaning-head. Fig. 3 is an end view of part of the driver. Fig. 4 is a side elevation showing the connection for the cleaning-head.

The construction and shape of the head may be varied to suit the work.

As here shown, A represents the portion of a tube to be cleaned. The cleaning-head consists of a series of toothed disks B, having central perforations and adapted to fit upon a square or other suitably-shaped shank C, upon which the disks are locked by means of a nut, as shown at D, and a holding-key E prevents the nut from turning. The peripheries of the disks B are toothed, as shown, and the teeth are arranged to alternate with each other, as plainly shown in Figs. 1 and 2, and by reason of the rectangular or other equivalent shape of the shaft or spindle C the teeth of the disks will be held in their relative position and not allowed to turn upon the shaft. By this construction the action of the teeth is made exceedingly effective for cleansing purposes.

The rear section of the cleaning-head is here

shown as semiglobular, the teeth being cut into the largest diameter of this section.

The shaft C has its rear end formed into a ring, as at C', and this engages with a corresponding ring or link F, formed by bending a rod so that this ring is the bight or central portion. The arms cross each other, extending outwardly, as shown at F', thence are bent parallel with each other, and finally are bent outwardly, as at F², so that the ends may engage with the staples or standards G of the driver, where they are locked by pins H, which pass through holes in the staples G, the arms F² passing beneath these pins and being securely locked in place thereby.

The driver consists of a disk I, having holes J made diagonally through and around its periphery, and water is admitted into these holes through openings K, made in the flat disk-face L, which forms the front of the supply-pipe M, through which water under pressure is brought to the wheel or driver. This wheel or driver consists of a central steel hub I', upon which the peripheral portion I is shrunk or otherwise secured. The face of the part I which is adjacent to the surface L is grooved or channeled, and the surface L is correspondingly grooved or channeled to form a race or runway for balls P, which fit therein. The opposite face of the hub or part I', which projects slightly from the face of the part I, is also grooved or channeled, and the disk Q, fitting against this face, is correspondingly channeled to receive the balls R, thus forming a ball-bearing upon opposite sides of the driver.

The driver turns upon a spindle S, which passes through the plate L, through the hub I', and through the disk Q, and by means of lock-nuts T upon the outer end the parts are adjusted and held together, so that the face of the driver I runs in close contact with the face of the disk L, and the water-supply passages K being disposed so as to deliver into the inclined passages J of the wheel the latter will be driven by the medium delivered thereto under pressure. This is brought into the head M by means of a flexible hose or equivalent connection, as shown at N.

The operation of the apparatus will then be as follows: The head B being inserted into

- the tube, power is applied to rotate it by delivering the water or other medium under pressure into the head M, and passing through the buckets of the driver the latter is rotated 5 at a high speed and the water passing through is also delivered into the tube or flue to be cleaned. As the head B is of considerably smaller diameter than the interior of the tube and as the connection between the driver 10 is made by the rings or links C and F is practically a universal joint, the high rate of speed gives two distinct motions to the head or cutter—first, the rotary motion, due to the water-motor, and, second, a centrifugal gyratory spiral motion, due to the contact of the teeth on the cutter-head on the tubes and the fact that the head is smaller than the interior of the tube. The direction of this gyratory motion is opposite to the spinning or rotary movement, and it has a pounding and smashing effect, which rapidly dislodges the scale within 15 the tube, while the current of water delivered through the driver constantly washes it away. When used for cleaning scale from the outside of fire-tube, it is effected by the rapid rotation of the head and the constant hammering upon the inside of the tubes. The form of the head may be altered to suit the class of work to be done. 20
- 30 To clean the interior of the tubes of fire-tube boilers, a wire brush is substituted for the cutters and the motor is driven by steam, which takes out every particle of soot from the tubes and leaves them as clean as when new.
- 35 The flexible joint connection allows the device to operate with equal efficiency in crooked tubes.
- Having thus described my invention, what I claim as new, and desire to secure by Letters 40 Patent, is—
1. A boiler-tube cleaner comprising a head composed of disks of successively-decreasing diameters, a driver and means for rotating the same, said driver and head each having a meeting portion disposed in its longitudinal central line and formed as a member of a universal coupling whereby the head is both 45 rotated and caused to gyrate independently and uncontrolled within the tube.
  2. A boiler-tube cleaner consisting of a head having a smaller diameter than the interior of the tube and including independent disks of successively-decreasing diameters, and each disk provided with a toothed periphery, a driver by which rotary motion is imparted, and a universal-joint coupling between the 50 driver and head and in line with the central longitudinal line of the driver and head whereby the latter is loosely hung and both rotated 55 and gyrated within the periphery of the tube.
  3. A boiler-tube cleaner consisting of a head composed of independent removable disks having toothed peripheries, said disks being

of successively-smaller diameter than the rearmost ones, a stem upon which the disks 65 are fixed so that their teeth alternate with each other, a driver and means for rotating the same, and a universal joint composed of connected members one of which projects from the head and the other from the driver 70 in the longitudinal central line thereof.

4. A boiler-tube cleaner consisting of a head, with exteriorly-toothed sections, a rectangular stem upon which said sections are fixed so that their teeth alternate with each other, 75 a ring formed at the rear of the stem, a rotary driver having lugs or standards projecting from its face, yoke-arms bent to interlock with said standards and be secured thereto and a ring formed in the bight of said yoke 80 connecting with the ring at the rear of the cleaning-head whereby a universal-joint connection is formed between the driver and cleaning-head.

5. In a boiler-tube cleaner, a head having 85 exteriorly-toothed disks, a stem or shank to which said disks are removably fixed, a universal-joint connection consisting of interlocking rings, one of which is formed upon the stem or shank of the head and the other 90 upon a yoke, a driver consisting of a wheel having inclined peripheral openings, standards projecting from the face of said wheel, with which standards the arms of the yoke are removably engaged and interlocked and 95 a water-supply head having perforations through which water is delivered into the wheel-buckets to revolve the latter substantially as described.

6. A boiler-tube cleaner and a driver therefor consisting of a head having a flat disk forming its front end, with perforations for the discharge of water and a pipe through which water is supplied under pressure, a wheel having diagonally-disposed holes made 105 through it on the line of the supply-passages of the head, a spindle by which the wheel is connected with the head, ball-bearings interposed between the face of the wheel and the contiguous face of the head, a disk or collar 110 exterior to the wheel with corresponding ball-bearings and lock-nuts fitting the spindle and serving to hold and adjust the wheel with relation to the head, a cleaner-head having a centrally-located stem formed as a member 115 of a universal coupling and a yoke extension from the face of the wheel and formed with an engaging member of said coupling disposed in line with the axis of the wheel.

In witness whereof I have hereunto set my hand.

ALVA A. PATTON.
